UNITED STATES PATENT OFFICE.

ANNA E. WHITMORE AND PERCIS A. WHITMORE, OF NOKOMIS, ILLINOIS.

DESIGN FOR A DISH AND FRUIT SIMULATION.

46,383.

Specification for Design.

Patented Sept. 8, 1914.

Application filed July 17, 1914. Serial No. 851,651. Term of patent 3½ years.

To all whom it may concern:

Be it known that we, ANNA E. WHITMORE and PERCIS A. WHITMORE, citizens of the United States, residing at Nokomis, in the county of Montgomery and State of Illinois, have invented a new, original, and ornamental Design for a Dish and Fruit Simulation, of which the following is a specification, reference being had to the accompanying drawing, forming part thereof.

The figure is a perspective view of a dish

and fruit simulation, showing our new design.

We claim:—

The ornamental design for a dish and fruit simulation, as shown.

ANNA E. WHITMORE.
MISS PERCIS A. WHITMORE.
